UNITED STATES PATENT OFFICE.

CARL M. HEDMAN, OF CHICAGO, ILLINOIS, ASSIGNOR TO HEDMAN MANUFACTURING COMPANY, OF CHICAGO, ILLINOIS, A CORPORATION OF ILLINOIS.

CHECK-PROTECTOR.

1,270,517.

Specification of Letters Patent. Patented June 25, 1918.

Application filed August 7 1916. Serial No. 113,441.

To all whom it may concern:

Be it known that I, CARL M. HEDMAN, a citizen of the United States; residing at Chicago; in the county of Cook and State of Illinois, have invented a certain new and useful Improvement in Check-Protectors, of which the following is a full, clear, concise, and exact description; reference being had to the accompanying drawings, forming a part of this specification.

My invention relates to protectors for checks and other commercial paper, and more particularly to the printing and shredding mechanism whereby the protector is capable of effecting a suitable, neat and non-eradicable impression upon checks and the like. The improvements characteristic of my present invention are particularly applicable to devices of the class shown and described in United States Letters Patent to Ivan Engstrom, No. 1,156,000; granted October 5, 1915, and co-pending application of Douglas F. Fesler, Serial No. 81,604; filed March 2, 1916. Generally speaking, devices of the class shown in the patent and co-pending application aforesaid comprise a plurality of ordered marking elements or sectors; each of which is provided with a set of consecutively arranged numeral type arranged to cooperate with a suitable platen, the several sets of numeral type corresponding to the various orders and being independently adjustable, as distinguished from devices wherein all of the type are carried upon a single drum; whereby the impression made upon any instrument may correspond exactly in dollars and cents with the amount for which the instrument is drawn.

In the particular embodiment of my invention hereinafter described the stationary platen with which the ordered sets of type numerals are arranged to cooperate has formed on the upper face thereof a plurality of non-parallel arcuated depressions or grooves with substantially moon or crescent shaped ridges intervening between the several depressions or grooves. The several grooves or depressions are desirably struck in the form of arcs of equal circles having different and regularly spaced centers along the medial transverse plane of the platen, it being understood that the platen is disposed below the ordered type carriers or

sectors and transversely of the planes in which the latter operate.

Each of the type carried by the ordered type carriers is provided with a plurality of non-parallel arcuated ridges and intervening depressions or grooves arranged to co-operate with the grooves and ridges of the platen when the type is brought into operative relation with the platen. The grooves and ridges of the type similar to the corresponding grooves and ridges of the platen are arcuated and non-parallel, the several grooves and depressions of each type lying in the arcs of equal circles having their centers at different points along a medial line extending transversely of the type.

It will be understood that when the improvements of my invention are incorporated in machines of the class shown and described in the patent and co-pending application hereinbefore referred to, the "and" and "cts" type as well as the "Pay \$" or "Not over \$" type of the limiting type bar are provided with alternate and non-parallel arcuated grooves and ridges corresponding to the grooves and ridges carried by the type of the adjustable type carriers or sectors.

In addition to the fact that by employing the hereinbefore mentioned arrangement of non-parallel co-operating grooves and ridges I am enabled to produce a non-eradicable impression upon a check or the like pleasing to the eye and one which does not materially weaken the paper upon which the impression is made, I find that the particular arrangement of co-operating grooves and ridges serves properly to center each of the numeral type as it is brought into operative relation with the platen, thus insuring perfect alinement of the several digits impressed upon a check. This is a very important consideration in machines of the class wherein the several type which serve to effect the impression of a number upon a check are carried by different ordered type carriers or sectors, as previously explained.

In addition to the features before mentioned the platen and co-operating type of my invention provide three different kinds of surfaces to wit, "slitting or shredding surfaces," "inking surfaces" and "printing surfaces," as distinguished from somewhat similar arrangements of the prior art which,

properly speaking, comprise but two general classes of surfaces to wit, "slitting or shredding surfaces" and "inking surfaces."

These and other characteristic features of my invention are fully set forth in the following detailed description, wherein reference is made to the accompanying drawings, in which—

Fig. 1 is a view partially in side elevation and partially in vertical section illustrating a machine of the class with which I prefer to associate the improvements of my present invention;

Fig. 2 is a view partially in front elevation and partially in vertical section of the machine shown in Fig. 1;

Fig. 3 is an enlarged top plan view of the platen forming a part of my invention;

Fig. 4 is a fragmentary view of the platen illustrating the eccentric and non-parallel relation of the grooves and ridges therein;

Fig. 5 is a fragmentary sectional view of the platen taken in a medial transverse plane thereof;

Fig. 6 is a cross sectional view of the platen taken on the lines 6—6 of Fig. 3;

Fig. 7 is an enlarged view of one of the numeral type arranged to coöperate with the platen, the figure "2" being chosen for the purpose of illustration;

Fig. 8 is a side elevational view of the type shown in Fig. 7;

Fig. 9 is a greatly enlarged view in cross section taken on the line 9—9 of Fig. 7;

Fig. 10 is a greatly enlarged view of a type carrying the figure "5" clearly to illustrate the eccentric and non-parallel relation of the arcuated grooves and ridges carried by the type, and

Fig. 11 is an enlarged sectional view illustrating how the grooves and ridges of the type coöperate with the grooves and ridges of the platen when an impression is made upon a check or other instrument.

Similar characters of reference refer to similar parts throughout the several views.

For the most part it will be unnecessary to describe in detail the construction and operation of those parts of the check protector mechanism other than the type and platen, as said parts are fully shown and described in the patent to Ivan Engstrom and the co-pending application of Douglas F. Fesler hereinbefore mentioned. I shall, therefore, make but brief reference to the construction of those parts of the machine other than the platen and type which coöperate therewith.

Referring first to Figs. 1 and 2, it will be noted that the mechanism comprises a suitable base 15 which carries a stationary platen denoted by the reference letter P, the construction of which will be more fully hereinafter described. Pivoted to the rear end of the base 15 at 16 is a casing 17, normally held in the position shown in Fig. 1

by a plurality of springs, one of which is illustrated at 18, the arrangement being such that the casing 17 may be struck downwardly by depressing a lever 19 when an impression is to be made upon a check. The lever 19 is pivoted to a post or bracket 20 extending upwardly from the base, and the said lever is also connected through a link 21 with the top of the casing 17.

Supported by the casing 17 are two shafts 22 and 23 denoted by the reference numerals 22 and 23 and disposed one above the other, as is most clearly illustrated in Fig. 1. Journaled upon the shaft 22 is a plurality of ordered type carriers or sectors, each of which is indicated by the reference numeral 24 and is provided with a key lever 25, whereby any one of the type carried by the sector may be brought opposite the platen P. Each of the sectors 24 is conveniently in the form of a metal stamping and has cast thereon a bar 26 which carries the consecutively arranged numeral type indicated in Figs. 1 and 2 by the reference letter T. I may as well point out at this time that the bar 26 and type T formed integral therewith and the platen as well are desirably formed of the alloy now generally known commercially as alemit, that said parts are preferably formed in a die casting machine, and that the bar 26 and type T are desirably cast upon the sectors 24. It will thus be seen that each of the type carriers or sectors may be variably adjusted by its associated key lever 25. Each of the sectors 24 is desirably provided with a tooth portion 27 arranged to coöperate with a suitable retaining pawl 28, whereby the sector is held in any position to which it may be moved.

Positioned adjacent the type carrier of lowest order is a stationary type carrier 29, carried by the shaft 22 and connected also with the shaft 23. This stationary type member carries type arranged to coöperate with the platen to impress upon the check some indicia to the right of the digit impressed by the type of lowest denomination, and may carry, if desired, the letters "cts" indicating "cents." A second stationary type carrying member is provided at 30 and carries type arranged to coöperate with the platen to impress the word "and" upon the check and so form a definite division between the dollars characters and cents characters. The type carrying sectors lying between the stationary type carriers 29 and 30 as well as the sector lying immediately to the left of the stationary type carrier 30 (Fig. 2) are so arranged that when they are in their normal or home positions they will print "0." The other four sectors are normally out of the printing line, so that if none of the printing sectors are normally set the sectors of the three lowest orders, that is, the two "cents" sectors and the first "dol-

lars" sector, are the only ones which will print.

At 31 is illustrated a limiting type bar 5 slidably mounted upon a support 32 carried by the shafts 22 and 23. This type bar may carry type arranged to coöperate with the platen to impress upon the check such indicia as "Pay \$" or "Not over \$." I shall not here go into a detailed description 10 of the means for operating and controlling the limiting type bar 31, as these parts are clearly shown and described in the patent and copending application previously mentioned. It will suffice to say that when the lever 19 is operated to strike down the casing 17 and thus impress upon a check an indication corresponding to any set-up, the limiting type bar is moved to lie adjacent the sector of the highest order which has been 15 moved to effect the desired set-up.

At 33 is shown an inking pad which inks each of the type as it is moved to "set position." It will suffice to say that this inking pad is swung out of its position above the 20 platen P when the casing 17 is struck downwardly to effect an impression upon a check or other instrument.

As thus far described the mechanism follows very closely the arrangement disclosed 25 in the Fesler application just mentioned. I shall now proceed to describe the construction and coöperation of the type and platen with which my present invention is more particularly concerned.

30 The platen P is illustrated in detail in Figs. 3, 5 and 6. The platen is desirably a bar of alemite as previously pointed out and is disposed transversely of the base 15 and located beneath the stationary type carriers 29 and 30 and sliding type bar 31. Formed in the upper face of the platen P, as is most clearly illustrated in Fig. 3, are 35 a plurality of eccentric arcuated grooves illustrated at p^1 and it will be noted that adjacent eccentric grooves or depressions p^1 are separated by moon or crescent shaped ridges p^2 . The several grooves p^1 lie in arcs of equal circles having their centers located at different points along the 40 medial transverse plane of the platen. Thus, as is clearly illustrated in Fig. 4, the arcuated groove or depression p^1-a lies in the arc of a circle having as its center the point a , the groove or depression p^1-b lies in the 45 arc of an equal circle having its center at the point b , whereas the groove or depression p^1-c lies in the arc of a circle having as its center the point c . Thus it will be seen all of the depressions or grooves in the 50 upper face of the platen are arcuated and eccentric, each to the others, although all of the arcuated grooves lie in the arcs of equal circles.

The several figures formed upon each of 55 the type bars 26 of the sectors 24 have

formed therein a plurality of alternate ridges and grooves illustrated respectively at t^1 and t^2 in Figs. 7 and 10. Attention is directed to the fact that each of the ridges t^1 has a tapered cross section and that each of the ridges t^1 lies in the arc of a circle having its center lying in a medial line extending transversely of the figure upon which the ridges are formed. Thus as illustrated in Fig. 10 the ridge t^1-a lies in the 70 arc of a circle having as its center the point a , the ridge t^1-b lies in the arc of an equal circle having its center at the point b , etc. It will thus be seen that each of the figures provided with alternate grooves and ridges 75 as shown in Figs. 7 and 10 may be brought into position over the platen, so that the ridges t^1 of the figure register with the arcuated grooves p^1 of the platen. In a like manner the crescent or moon shaped ridges 80 p^2 of the platen register with the grooves t^2 which intervene between the several arcuated ridges t^1 of each of the figures.

Assuming that the check protector shown in Figs. 1 and 2 is provided with a platen 90 and type faces of the class just mentioned, and that an impression is to be made upon a check. The several key levers 25 are shifted to the positions necessary to bring the proper figures above the platen, and the 95 check is inserted so that it rests over the platen P, the lever 19 is then depressed to bring the selected figures down toward the platen and also carrying the stationary type bars 29 and 30 down toward the platen. 100 At the same time the limiting type bar 31 is shifted to a position adjacent the figure carrying sector of the highest operating order, the several grooves and ridges of the type faces and platen intermeshing when 105 the lever 19 is thus depressed, and the check or other instrument illustrated at C is thus mutilated and ink carried therein to form a non-eradicable impression thereon. The 110 relative positions of the grooves and ridges of the platen and type when an impression is being made are illustrated in Fig. 11.

I wish to have it understood that the ridges t^1 of the figures are struck in the arcs of circles equal to the circles in the arcs 115 of which the arcuated groove p^1 of the platen are struck. Therefore, the alternate grooves and ridges of each one of the figure or other type can only mesh with the grooves and ridges of the platen when the type lies 120 in a position such that its medial transverse line lies in the medial transverse plane of the platen. In other words, the line of centers of the circles in which the ridges of the type faces are struck must lie in the 125 medial transverse plane of the platen, or stated differently, directly above the line of centers of the circles in which the arcuated grooves of the platen are struck. I find that the several type as brought into mesh 130

with the platen tend to find their proper centers, and that therefore proper alinement of the impressions made by the several type is assured. This is an extremely important 5 consideration when my invention is incorporated in a machine of the class herein described, wherein the numeral type for the several orders are mounted upon different type carrying sectors and are thus brought 10 separately to the printing line.

As is most clearly illustrated in Fig. 11, the intermeshing grooves and ridges of the type and platen of my invention provide 15 three different kinds of surfaces. The sloping surfaces of the type ridges t^1 serve as inking surfaces and tend to carry the ink into the mutilated portions of the check when an impression is made. The points of the type ridges t^1 and the upper edges of 20 the platen ridges p^2 serve as slitting or shredding surfaces. The upper surfaces of the platen ridges p^2 coöperating with the bottoms of the type grooves t^2 serve as printing surfaces. Thus, when an impression 25 is made upon a check, three different sets of surfaces of type and platen come into play to perform three different functions to wit, shredding, inking and printing. I believe that this arrangement of type and 30 platen surfaces is different from any of the arrangements of the prior art, wherein the paper is shredded, as all of the devices of the prior art with which I am familiar, properly speaking, comprise but two sets of 35 surfaces to wit, shredding and inking surfaces, and there are no surfaces which effect actual printing.

What I claim as new and desire to secure by Letters Patent of the United States is:

40 1. In a device of the class described the combination of a plurality of adjustable ordered marking elements, each having a plurality of type thereon, a platen, means for moving the marking elements toward 45 the platen, a plurality of arcuate grooves in the platen, the several grooves in the platen lying in arcs of equal circles having their centers at different points in a line in the medial transverse plane of the platen, and 50 a plurality of arcuate ridges on each of the type carried by the marking elements, the ridges of each type lying in the arcs of equal circles having their centers at different points along a medial line extending transversely 55 of the type, the curvature of the type ridges being the same as the curvature of the platen grooves.

2. A device of the class described comprising a plurality of ordered marking elements, 60 each provided with a plurality of type, a platen extending transversely of the planes in which said marking elements operate, means for effecting relative movement to cause engagement of the platen and type, 65 a plurality of eccentric arcuate grooves in

the platen, the several grooves lying in the arcs of equal circles having their centers regularly spaced along the medial transverse plane of the platen, and a plurality of ridges on each type arranged to mesh with the 70 grooves of the platen when the type is brought into engagement with the platen.

3. A device of the class described comprising a plurality of ordered marking elements, each carrying a series of type, a 75 platen, means for effecting relative movement to cause engagement of the type and platen, a plurality of non-parallel arcuate grooves in the platen, and a plurality of ridges on each type arranged to mesh with 80 the grooves of the platen when the type is caused to engage the platen.

4. A device of the class described comprising a type carrier having a plurality of printing characters mounted thereon, a 85 platen, means for causing the type carrier and platen to move one toward the other, a plurality of non-parallel arcuate grooves in the platen, said grooves lying in the arcs of equal circles having their centers at 90 equally spaced points along the platen, and a plurality of ridges on each printing character arranged to mesh with the grooves of the platen when the character is caused to engage the platen.

5. A device of the class described comprising a platen; a plurality of printing characters designed to be brought into engagement with the platen to impress a non-eradicable impression upon a sheet disposed 100 between the platen and printing characters, a plurality of arcuate grooves in the platen, the several grooves lying in the arcs of equal circles having their centers at different points in the same line along the platen, 105 and a plurality of ridges on each printing character, the several ridges of each character lying in the arcs of equal circles having their centers at different points in a line extending across the printing character, the 110 curvature of the ridges of the printing characters being the same as the curvatures of the platen grooves.

6. A device of the class described comprising a marking element, a plurality of 115 printing characters carried thereby, a platen, a plurality of non-parallel arcuate grooves in the platen, and a plurality of non-parallel ridges on each printing character arranged to mesh with the grooves of the 120 platen when the printing character is moved into engagement with the platen.

7. A device of the class described comprising a plurality of printing characters disposed side by side, a platen with which 125 the printing characters are arranged to engage, a plurality of arcuate grooves in the platen, said grooves lying in the arcs of equal circles having their centers in the same line across the platen, and a plurality of 130

arcuate ridges on each printing character having the same curvature as the platen grooves whereby the said ridges register with the platen grooves and the printing characters are alined when the latter are caused to engage the platen.

8. A device of the class described comprising in combination with a type carrier having a plurality of printing characters thereon, a platen, a plurality of non-parallel arcuate ridges in each printing character, and a plurality of non-parallel arcuate grooves in the platen having substantially the same curvature as the printing character ridges whereby the ridges of each printing character are adapted to register with the grooves of the platen when the printing character is caused to engage the platen.

9. A device of the class described comprising a plurality of printing characters, each having a plurality of non-parallel ridges thereon, a platen with which said characters are arranged to engage, and a plurality of non-parallel grooves in the platen arranged to mesh with the non-parallel ridges of the printing characters when the latter are moved into engagement with the platen.

10. A machine of the class described comprising a platen having a plurality of arcuate grooves therein, and a printing character arranged to engage with the platen, said printing character having arcuate ridges thereon arranged to engage with the arcuate grooves of the platen.

11. In a structure of the class described, the combination with a stationary platen, of a plurality of separate type sectors, a shaft rotatably supporting said type sectors side by side in position to co-act with said platen, means for adjusting said type sectors upon said shaft to bring the desired type into position to co-act with said platen, and means for alining the selected type comprising co-acting complementary, non-parallel arcuate grooves and ridges formed in the faces of said platen and in said type, the sides of said ridges being beveled.

12. In a structure of the class described, the combination with a stationary platen, of a plurality of separate type sectors, means for rotatably supporting said type sectors side by side in position to co-act with said platen, means for adjusting said type sectors upon said shaft to bring the desired type into position to co-act with said platen, and means for alining the selected type compris-

ing co-acting complementary non-parallel arcuate grooves and ridges formed in the faces of said platen and in said type.

13. In a structure of the class described, the combination with a stationary platen, of a plurality of separate type sectors, means for rotatably supporting said type sectors side by side in position to co-act with said platen, means for adjusting said type sectors upon said shaft to bring the desired type into position to co-act with said platen; and means for alining the selected type comprising co-acting complementary arcuate grooves and ridges formed in the faces of said platen and in said type.

14. In a structure of the class described, the combination with a stationary platen, of a plurality of separate type sectors, means for rotatably supporting said type sectors side by side in position to co-act with said platen, means for adjusting said type sectors upon said shaft to bring the desired type into position to co-act with said platen, and means for alining the selected type comprising co-acting complementary grooves and ridges formed in the faces of said platen and in said type.

15. In a structure of the class described, the combination with a platen, of a plurality of separate type sectors, means for rotatably supporting said type sectors side by side in position to co-act with said platen, means for adjusting said type sectors upon said shaft to bring the desired type into position to co-act with said platen and co-acting means on the coacting faces of said platen and type sectors for alining the selected type.

16. In a structure of the class described, the combination with a platen, of a plurality of separate type sectors, means for rotatably supporting said type sectors side by side in position to co-act with said platen, means for adjusting said type sectors upon said shaft to bring the desired type into position to co-act with said platen and co-acting means on said platen and the peripheries of said type sectors for automatically alining the selected type as said type are brought into co-acting relation with said platen.

In witness whereof, I hereunto subscribe my name this 4th day of August, A. D. 1916.

CARL M. HEDMAN.
